GAME BOARD

Paul E. Wahlberg and Nobel V. Johnson,
Pomona, Calif.

Application September 7, 1948, Serial No. 148,493

Term of patent 3½ years

(Cl. D34—5)

To all whom it may concern:

Be it known that we, Paul E. Wahlberg and Nobel V. Johnson, citizens of the United States of America, both residing at Pomona, in the county of Los Angeles and State of California, have invented a new, original, and ornamental Design for a Game Board, of which the following is a specification, reference being had to the accompanying drawing, forming a part thereof.

Figure 1 is a front elevational view of a game board, showing our new design;

Figure 2 is a rear elevational view thereof; and

Figure 3 is a side elevational view thereof.

The dominant features of our design reside in that portion shown in full lines in the drawing.

We claim:

The ornamental design for a gameboard, as shown and described.

PAUL E. WAHLBERG.
NOBEL V. JOHNSON.
